INVENTOR.

Charles H. Louttit,

BY
Geo. P. Kammel
ATTORNEY.

UNITED STATES PATENT OFFICE

CHARLES H. LOUTTIT, OF PORTLAND, OREGON

INCANDESCENT LAMP

Application filed December 4, 1929. Serial No. 411,587.

This invention relates to an incandescent lamp constructed in a manner as hereinafter set forth, in which the globe is formed with an inner wall and an outer wall to provide a 5 vacuum space therebetween, with such space extending around the supporting stem for the lead-in wires and further extending into the plug for connecting the lamp with a socket, thereby preventing the outer globe from becoming heated in the use of the lamp and further preventing the socket fixture from becoming heated in such use.

One of the objects of the invention is to prevent the radiation of heat from the globe 15 and socket fixture when the lamp is in use, thereby particularly adapting the lamp for use in theaters and the like, where the heat from ordinary incandescent lamps often causes discomfort to both audience and artists, and further adapting the lamp for use in refrigerating plants, where the heat from ordinary lamps has a tendency to counteract the cold temperature produced in the plant.

A further object of the invention is to provide an incandescent lamp having the foregoing characteristics which is adapted for use in outside lighting in extremely cold climates without any likelihood of the globe bursting 25 due to its contact with icy blasts of wind and the like.

A further object of the invention is to reduce to a minimum the likelihood of fire damage to the electrical fixtures associated with the lamp by maintaining the socket plug in a cool condition, and further to permit the use 35 of shades of ignitable material, such as tissue paper, without any likelihood of the shade becoming ignited by its contact with the globe or socket plug.

With the foregoing and other objects in view, the invention consists of the novel construction, combination and arrangement of parts as hereinafter more particularly described, and as illustrated in the accompanying drawings wherein is shown an embodiment of the invention, but it is to be understood that the description and drawings are to be taken as illustrative and that the invention is intended to be limited only by the scope of the claims hereunto appended.

In the accompanying drawings wherein like numerals are employed to designate like parts throughout the same:—

Figure 1 is a sectional plan of a lamp constructed in accordance with this invention. 55

Figure 2 is a section taken on the line 2—2 of Figure 1.

Referring to the drawings in detail, the numeral 1 designates an externally threaded socket plug which may be of any well known construction and from which projects a glass stem 2 for supporting the usual lead-in wires 3 which are adapted for connection with a suitable filament, not shown. Supported on the stem 2 is a globe consisting of an outer 60 wall 4 and an inner wall 5.

The outer wall 4 is formed with a cylindrical neck portion 6 which encircles and snugly engages the stem 2 and extends into a recess 7 formed in the inner end face of the 70 plug 1. The neck portion 6 merges into the main body portion 8 of the outer wall 4, such main body portion extending in contacting relation to the wall of the recess 7 as indicated at 9, and in spaced relation to the plug 75 having its contour broken by a series of angles indicated at 10.

Preferably formed integrally with the neck portion 6, as indicated at 11, is the neck portion 12 of the inner wall 5. The neck portion 12 extends in parallel spaced relation to the neck portion 6 and merges into the main body portion 13 of the inner wall 5, such main body portion 13 being disposed within 80 and extending in spaced parallel relation to the main body portion 8 of the outer wall 4. Thus it will be seen that a space 14 is provided between the walls 4 and 5, with a portion 15 of the space extending into the recess 7 of the plug, and with a neck portion 16 of the space being disposed in circumferential relation to the stem 2. The space 14, as well 85 as the interior 17 of the inner wall 5 is exhausted of air in any well known manner, thereby providing a vacuum type inner globe 90 disposed within and spaced from a vacuum type outer globe.

It is thought the many advantages of an incandescent lamp in accordance with this invention will be readily apparent, and al- 100

though the preferred embodiment of the invention is as illustrated and described, it is to be understood that changes in the size, shape and arrangement of parts may be resorted to, so long as such changes fall within the scope of the invention as defined in the appended claims.

What I claim is:—

1. An incandescent lamp comprising, a
10 socket plug, a lead-in wire supporting stem
projecting from the plug, and a vacuum-type
globe carried by the stem, said globe includ-
ing an outer wall having a neck portion ex-
tending longitudinally of the stem in encir-
15 cling relation thereto and snugly engaging
the stem and further having a main body
portion merging into the neck portion, said
globe further including an inner wall hav-
ing a neck portion fused with the neck por-
20 tion of the outer wall and extending in par-
allel spaced relation thereto, said inner wall
further having a main body portion merg-
ing into the neck portion thereof and extend-
ing in parallel spaced relation to the main
25 body portion of the outer wall.
2. An incandescent lamp comprising, a
socket plug formed in its inner end face with
a recess, a lead-in wire supporting stem pro-
jecting from the plug, and a vacuum-type
30 globe carried by the stem, said globe includ-
ing an outer wall having a neck portion en-
circling and snugly engaging the stem and
extending into said recess, said outer wall
further having a main body portion merg-
35 ing into the neck portion and extending in con-
tacting relation with the wall of the recess,
said globe further including an inner wall
having a neck portion fused with the neck
portion of the outer wall and extending in
40 parallel, spaced relation thereto, said inner
wall further having a main body portion
merging into the neck portion thereof and
extending in parallel spaced relation to the
main body portion of the outer wall.
- 45 In testimony whereof, I affix my signature
hereto.

CHARLES H. LOUTTIT.
